UNITED STATES PATENT OFFICE.

JOHN THOMAS SANDERS, OF ANDREWS, TEXAS.

LIFTING-JACK.

SPECIFICATION forming part of Letters Patent No. 663,932, dated December 18, 1900.

Application filed October 4, 1900. Serial No. 32,030. (No model.)

To all whom it may concern:

Be it known that I, JOHN THOMAS SANDERS, a citizen of the United States, residing at Andrews, in the county of Wood and State 5 of Texas, have invented a new and useful Lifting-Jack, of which the following is a specification.

The invention relates to improvements in lifting-jacks.

10 The object of the present invention is to improve the construction of lifting-jacks and to provide a simple, inexpensive, and efficient device adapted to be readily applied to that class of lifting-jacks having a vertically-movable screw and capable of enabling the jack to be readily connected with an object at the base of it, whereby the range of the lifting-jack will be materially increased.

15 The invention consists in the construction and novel combination and arrangement of parts hereinafter fully described, illustrated in the accompanying drawings, and pointed out in the claims hereto appended.

20 In the drawings, Figure 1 is a perspective view of a lifting-jack constructed in accordance with this invention. Fig. 2 is a vertical sectional view of the same.

25 Like numerals of reference designate corresponding parts in both figures of the drawings.

30 1 designates a horizontal bar arranged at the top of the vertically-movable screw 2 of a jack 3, provided at the top of the screw with the usual head 4, having apertures for 35 the reception of a bar or lever whereby the screw is rotated for operating the jack. The horizontal bar 1, which rests upon the top of the head, is provided with a central aperture 5, receiving a vertical journal or pivot 6, 40 formed integral with the head of the screw and provided with a flange 7. The flange 7, which is annular, extends horizontally from the upper end of the journal or pivot 6 and projects over the upper face of the horizontal bar to retain the latter in position. The

45 horizontal bar, which is designed to be constructed of steel or other suitable material, projects from opposite sides of the jack and is provided at its ends with vertical perforations for the shanks of eyebolts 8, which connect hooks or grapples 9 with the ends of the bar 1. The eyebolts, which are adapted to

turn freely in the openings at the ends of the horizontal supporting-bar, may be swiveled to the same in any suitable manner; but in 55 the accompanying drawings they are shown threaded and provided with nuts 10, whereby the hooks may be readily detached from the supporting-bar when desired. The hooks are provided at the upper ends of the shanks 60 with openings 11 and are linked into the eyes of the eyebolts, and the flexible connection between the eyebolt and the hook and the swivel connection between the latter and the supporting-bar enable the hook to be readily 65 arranged in any desired position to facilitate its engagement with the object to be lifted.

70 The lifting-jack, which possesses great strength and durability, is adapted for a great variety of purposes, as will be readily apparent, and it greatly increases the range and usefulness of an ordinary jack, as it will enable an object to be lifted from the ground by means of the hooks and then operated on by the jack proper. The object may be raised 75 by engaging the hooks with it until it is at an elevation which will admit of the placing of the jack beneath it. The object is held in this position until it is suitably propped or supported, after which the hooks are removed 80 from their engaging positions and the screw is positioned beneath the object. The jack may then be operated to lift the object to any desired height within its capacity.

85 It will be seen that the attachment is exceedingly simple and inexpensive in construction, that it possesses great strength and durability, and that it may be readily applied to the screw of an ordinary jack. It will also be apparent that the connections between the 90 hooks and the ends of the supporting-bar admit of the hooks being reversed and arranged in any desired position and that as the weight is received at points at opposite sides of the jack the latter will not upset.

95 What I claim is—

1. The combination with a jack having a screw provided at the top with a pivot, of a horizontal bar supported on the screw and provided with a central opening receiving the 100 pivot, whereby the bar is journaled on the screw and is adapted to swing freely around the same, said bar being provided at its ends with apertures, the eyes provided with shanks

extending through the apertures at the ends of the bar and swiveled to the latter, and the opposite hooks provided with openings and linked into the eyes, substantially as described.

2. The combination with a jack having a screw provided at the top with a pivot, a horizontal bar supported by the screw and provided with an opening to receive the pivot
10 and having apertures at its ends, the eyes located beneath the horizontal bar and provided with vertical shanks passing through the said apertures and adapted to turn freely therein and provided with threads, the nuts

engaging the threaded shanks and arranged 15 at the upper face of the horizontal bar, and the hooks having openings and linked into the said eyes, whereby they are flexibly connected with the horizontal bar, substantially as described.

In testimony that I claim the foregoing as my own I have hereto affixed my signature in the presence of two witnesses.

JOHN THOMAS SANDERS.
